UNITED STATES PATENT OFFICE.

HAYES SCHERMERHORN AND JUDD W. WEATHERWAX, OF LOS ANGELES, CALIFORNIA, SAID SCHERMERHORN ASSIGNOR OF HIS ENTIRE RIGHT TO MARY SCHERMERHORN, OF LOS ANGELES, CALIFORNIA.

WASTE-PIPE FLUSHING DEVICE.

Application filed April 13, 1923. Serial No. 631,885.

To all whom it may concern:

Be it known that we, HAYES SCHERMERHORN and JUDD W. WEATHERWAX, citizens of the United States, residing at Los Angeles, in the county of Los Angeles and State of California, have invented new and useful Improvements in Waste-Pipe Flushing Devices, of which the following is a specification.

10 Our invention relates to a flushing and cleaning device for drain or waste pipes, the principal object of our invention being to provide a relatively simple and practical device that may be easily and conveniently used and which is particularly designed to utilize the pressure of water for the flushing and cleaning of waste or drain pipes that lead from sinks, bath tubs, wash bowls and the like.

15 Further objects are, to provide a device of the character described, that is of relatively simple structure and capable of being easily and cheaply produced, to provide a flushing device that may be firmly secured 20 in position for use, and which, when properly applied will prevent leakage of the flushing water into the sink or bowl and further, to provide a flushing device that may be used without requiring any special 25 effort on the part of the user and without requiring the use of special tools or skilled labor.

With the foregoing and other objects in view, our invention consists in certain novel 30 features of construction and arrangement of parts that will be hereinafter more fully described and claimed and illustrated in the accompanying drawings in which:

Fig. 1 is a perspective view of our improved flushing device in position for use 35 in a sink and connected to one of the faucets that discharges water under pressure into said sink.

Fig. 2 is a sectional view of the device applied for use.

Referring by numerals to the accompanying drawings which illustrate a practical embodiment of our invention, 10 designates an inverted cup shaped member, preferably 40 conical in form and composed of rubber or a composition of which rubber is the principal ingredient.

The lower edge of this hollow conical body terminates in a bead or flange 11 hav-

ing a flat under face in which is formed an 55 annular groove 12, which, when the device is applied for use, constitutes a vacuum suction chamber as will be hereinafter more fully described.

Formed at the apex of the body 10 is a 60 block 13 of the same material as said body and passing axially through said block is a rod 14, the lower end of which is provided with a short, tapered threaded shank 15.

Formed integral with or fixed to rod 14, 65 above the body 10 is a disc 16 that normally fits snugly on top of block 13 and the upper end of said rod terminates in a pair of wings 17 that may be readily engaged between the thumb and fingers when said rod 70 is to be rotated.

Connected to the upper portion of the body 10, adjacent to block 13, is one end of a flexible tube 18, preferably rubber, the other or free end thereof being formed with 75 a relatively thick wall 19 that terminates in annular bead 20.

Formed in the inner face of this tube and within the bead 20 is an annular groove 21, which, when the end of the tube is applied 80 to a faucet or other source of water under pressure, performs the functions of a vacuum suction chamber and tends to cause the tube to adhere to and retain its connection with said faucet.

When our improved flushing device is applied for use, the free end of the tube 18 is slipped onto the end of the faucet and member 10 is positioned on the bottom of the sink, directly over the strainer or perforated plate that is located over the mouth or inlet end of the waste pipe.

Rod 14 is now rotated so as to cause threaded shank 15 to engage in one of the perforations in the strainer plate, and as 95 this action is continued, the flat under face of flange 11 will be forced or pressed against the surface upon which it rests.

Under a certain degree of pressure, a portion of the air trapped within groove 12 100 will be expelled therefrom, thereby producing sufficient partial vacuum to cause the under side of the flange to adhere to the supporting surface by the resulting suction and consequently a leak proof joint is 105 formed between the lower edge of the body 10 and the surface upon which it rests.

As the faucet to which the tube is con-

nected is opened, the water, under pressure, will rush through tube 18 and hollow body 10, thence through the strainer plate and thence through the waste pipe, thereby thoroughly flushing the latter and carrying off all accumulations therefrom.

Inasmuch as the rod 14 is always retained upon the hollow body our improved flushing device may be referred to as "one piece" 10 structure and in this respect, it has advantages over devices used for the same purpose but which have attachable and detachable parts that are liable to become misplaced and lost.

15 Thus it will be seen that we have produced a waste pipe flushing device that is of relatively simple structure, capable of being easily and cheaply produced, easily and quickly attached and detached and said 20 device being very effective in performing its intended functions.

Obviously the device is susceptible of minor changes in size, form and construction without departing from the spirit of 25 our invention, the scope of which is set forth in the appended claim.

We claim as our invention:

In a waste pipe flushing device, the com-

bination, with an inverted hollow conical member formed of flexible material, said member having a tube formed integral with its upper portion, and also having a block formed at its upper end, which block is provided with a vertically disposed bearing, of a rod journaled for rotation in said bearing and extending downwardly through the center of the hollow conical member, the lower portion of said rod extending below the plane occupied by the lower edge of said hollow conical member and terminating in an elongated tapered threaded shank that is adapted to be screwed into any one of the apertures in the strainer plate of a sink to clamp the hollow conical member firmly over said strainer plate, a disk rigidly fixed to the upper end of said rod and normally bearing on the block at the top of the hollow conical member so as to provide a water-tight joint between said rod and its bearing, and ears on the upper end of said rod.

In testimony whereof we have signed our names to this specification.

HAYES SCHERMERHORN.
JUDD W. WEATHERWAX.
